(57) **CLAIM**

I claim the ornamental design for a cigar cutter, as shown and described.

DESCRIPTION

The claimed cigar cutter is used for cutting the tip off of a cigar.

FIG. 1 is a front elevational view of a cigar cutter showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is a front elevational view thereof with the blade being pushed out and the handle being pulled to the opposite side.
